(57) **CLAIM**

We claim the ornamental design for a top element of a protective cap for a syringe, as shown and described.

DESCRIPTION

FIG. 1 is a perspective view at an angle from the front showing a top element of a protective cap for a syringe. FIG. 2 is a perspective view at an angle from the rear showing the top element of a protective cap for a syringe. FIG. 3 is a side view showing the top element of a protective cap for a syringe.

FIG. 4 is a front view showing the top element of a protective cap for a syringe; and,

FIG. 5 is a rear view showing the top element of a protective cap for a syringe.

The surface shading is for purposes of illustrating the character and/or contour of the surfaces of the claimed invention and forms no part of the claimed design.
